UNITED STATES PATENT OFFICE.

RUDOLF MÖTHE, OF SOLINGEN, GERMANY.

NAIL-SCISSORS.

1,383,556.

Specification of Letters Patent.

Patented July 5, 1921.

Application filed September 18, 1920. Serial No. 411,303.

To all whom it may concern:

Be it known that I, RUDOLF MÖTHE, a citizen of the German Republic, and residing at Solingen, Germany, have invented 5 certain new and useful Improvements in Nail-Scissors, of which the following is a specification.

This invention relates to improvements in nail-scissors, and more particularly to a 10 combination with the latter of a nail-cleaning instrument in such a way that when not in use the latter can be placed with a shell forming its handle over the sharp ends of the cutting-members of the pair 15 of scissors while it engages with its other end in a lug provided on one of said cutting-members, said shell forming thus a guard for the sharp ends of said cutting-members, while the nail-cleaning instrument 20 can be easily detached for intended use of both the latter and said pair of nail-scissors.

The annexed drawing shows the improved arrangement.

Figures 1 and 2 are respectively front 25 view and a side view of the same in combined position, while

Figs. 3 and 4 show respectively the pair

of nail-scissors and the nail-cleaning instrument in separated position.

a, b are the cutting-members of the pair 30 of nail scissors, *d* is a lug provided on one of said cutting members, *f* is the separate nail-cleaning instrument adapted when not in use to engage with its shell-like handle *e* over the sharp ends of said cutting-members 35 and with its free end *c* in said lug *d*.

What I claim, is:—

The combination with a pair of nail-scissors, of a lug on one of the cutting-members of the latter, and a separate nail-cleaning instrument having a shell-like handle and adapted when not in use to engage with the latter over the sharp ends 40 of the cutting-members of said pair of nail-scissors and with its free end in said lug, 45 substantially as and for the purpose set forth.

In testimony whereof I have hereunto set my hand in the presence of two subscribing witnesses.

RUDOLF MÖTHE.
